UNITED STATES PATENT OFFICE.

WILLIAM WERTS, OF CAMDEN, NEW JERSEY.

BOTTLE-STOPPER.

SPECIFICATION forming part of Letters Patent No. 365,286, dated June 21, 1887.

Application filed October 27, 1886. Serial No. 217,337. (No model.)

To all whom it may concern:

Be it known that I, WILLIAM WERTS, a citizen of the United States, residing at Camden, in the county of Camden and State of New Jersey, have invented new and useful 5 Improvements in Bottle and Jar Stoppers, of which the following is a specification.

My invention relates to improvements in bottle and jar stoppers; and it consists of the 10 peculiar combination of devices, and in the novel construction and arrangement of the various parts for service, substantially as hereininafter fully described, and particularly pointed out in the claims.

15 The object of my invention is to provide an improved bottle-stopper which can be readily adjusted to vary the leverage of the clamping devices, so that the packing can be more securely pressed upon the neck of the bottle to 20 hermetically seal the same, and effectually prevent the admission of air to the contents thereof.

It is well known that frequently stoppers of 25 beer and other bottles do not perfectly and tightly fit the same, and hence considerable time and labor are lost in fitting bottles with their stoppers at the time of their manufacture, and in refilling the bottle the stopper sometimes becomes loose, and is thus rendered un- 30 fit for use.

In my improved stopper I propose to provide the stopper proper with means for varying the distance of the rubber or other elastic packing thereof from the fulcrum or pivot of 35 the lever, so that when the stopper is loose, or does not properly fit the bottle, the stopper and its packing can be very readily adjusted to increase the power of the lever, and thereby force the packing upon the neck of the bottle 40 with greater force to hermetically seal the same.

A further object of my invention is to provide an improved stopper with means whereby the adjustment of the stopper proper can be effected after it has been applied to the bottle 45 to close the open end thereof, and after it has been filled with the liquid or other substance, the clamping devices being capable of a rotary movement on the bottle, while the packing and stopper are in position upon and close 50 the open end thereof, to effect the adjustment

of the fulcrum of the lever, all as will be more fully hereinafter described.

In the accompanying drawings, which illustrate a bottle-stopper embodying my present 55 improvements, Figure 1 is a perspective view. Fig. 2 is a side elevation showing the stopper closed in full lines and open in dotted lines. Fig. 3 is a top plan view showing the rotated position of the clamping devices in dotted 60 lines. Fig. 4 is a vertical sectional view on the line *x-x* of Fig. 3, showing the clamping devices closed. Fig. 5 is a detached perspective view of a modified form of my invention, and Fig. 6 is a central sectional view on the 65 line *y-y* of Fig. 5.

Referring to the drawings, in which like letters of reference denote corresponding parts in all the figures, A designates a bottle of any approved or preferred pattern, which is provided at its upper end with a reduced neck, *a*, 70 having an extended shoulder or ledge, *a'*, for a purpose presently described.

B designates the stopper proper, which is adapted to fit in the upper open end of the 75 neck of the bottle and to tightly close the same. The body of this stopper is preferably made of metal, and it has a central socket, *b*, formed therein, the walls of which are internally screw-threaded, as shown, to receive an 80 adjustable screw, *C*, which has a threaded shank that works in the threaded socket of the stopper-body, for a purpose presently explained. The stopper-body (shown in Figs. 1 to 4, inclusive,) is provided at its upper and lower 85 ends with right-angled flanges or ledges *b'* *b''*, which are formed integral therewith, and over its lower end, and over the lower flange, *b''*, thereof, is fitted a packing, *D*, of rubber or other like elastic substance, so as to more effectually close the mouth of the bottle. This 90 packing *D* is provided with an annular groove, *d*, into which the lower edge or flange, *b''*, of the stopper fits, so as to very securely and firmly connect the stopper and packing therefor together, and the upper edge of the packing is further provided with an annular flange or rim, *d'*, which is arranged beneath and concentric with the upper flange, *b'*, of the stopper, the edges of the rim *d'* of the elastic packing being extended or projected beyond the 100 edge of the flange *b'* of the stopper, so that

the flange or rim of the packing will be interposed between the upper edge of the bottle and the flange b' , so as to be closely and firmly pressed into contact with the bottle by the pressure of the said flange of the stopper thereon.

The adjusting-screw C of the stopper is provided at its upper end with a flat right-angled head, c , which is formed in a single piece therewith for strength and durability, and the opposite terminal ends of the said head are provided with vertically-disposed flanges c' , through which are formed transverse openings c'' , that are arranged in line with each other for the passage therethrough of the pivots of the lever F, as presently described. The head c and flanges c' form together a bracket, which I have shown as rigidly secured or fitted to the screw C.

The lever F is bent or formed from a single piece of stout wire, and it comprises the two sides $f f$, which are arranged parallel with each other, or substantially so, the short right-angled arms f' , which are bent at an angle to the lever arms or bars f proper, the pivot arms f'' , which are bent at right angles to the arms f' and in opposite directions from each other, so that they pass through the eyes of the flanges on the adjusting-screw, and the arms f''' , which are arranged at right angles to the sections or arms f'' , and are pivotally connected at their free ends to the bail G, by bending the said ends around the bail, as shown very clearly in Figs. 1 and 4. The pivot-arms f'' are arranged in line with each other and pass through the aligned openings in the lugs of the adjusting-screw, to pivotally connect the lever to the screw, so as to force the screw and the stopper into the open mouth of the bottle when the lever is pressed into a vertical position and against one side of the bottle, as will be more fully described presently.

The bail G is normally arranged in an upright or vertical position, and it comprises the side bars, g , and the transverse bar g' , all of which are bent from a single piece of wire. The lower ends of the side bars of the yoke are bent inwardly toward each other and the bottle, to provide short trunnions g'' , which are loosely fitted in aligned eyes h , formed in a collar or ring, H, which is fitted around the reduced neck of the bottle and beneath the flange or ledge a' thereof, to prevent vertical displacement of the same when upward pressure is exerted thereon by the bail when the lever forces the stopper to its seat. The collar is also formed of a single piece of wire, and the eyes h thereof are formed by giving the collar one or more coils at diametrically-opposite points in the same at the time of manufacturing the collar; and the collar is fitted loosely around the neck of the bottle, beneath the ledge or flange a' thereof, so as to turn or rotate around the bottle in adjusting the screw. When the lever is pressed against the sides of the bottle, as shown in Figs. 1, 2, and 4 of the drawings, the arms f' thereof assume a horizontal position, and thereby draw the arms f''

to a vertical position. As the arms f'' of the lever are connected to the stopper through the screw, the latter is forced downwardly and 70 presses the stopper into the open end of the bottle, so that the packing will be compressed within the bottle and the rim d' thereof pressed upon the upper edge of the bottle by the rigid upper flange, b' , of the stopper proper. When 75 the stopper is forced to its seat in the bottle by the action of the lever thereon, the arms f''' of the lever, which are pivotally connected to the bail, draw upon the bail and turn or force the same to a vertical position, and the 80 bail and adjusting-screw are arranged in line with each other and in the same vertical plane.

The operation of my invention is as follows: After the stopper has been properly applied to the bottle and the latter has been filled 85 with the liquid, the packing and stopper are adjusted to enter the open end of the bottle. In this position the bail assumes a slightly-inclined position, and the lever also lies in an inclined position, as shown in dotted lines in 90 Fig. 2 of the drawings. The free end of the lever is now depressed until it bears against the side of the bottle, and this movement of the lever simultaneously presses the stopper into the bottle, to tightly close the same, and 95 draws the bail to a vertical or upright position.

If it is found that the stopper does not tightly close the upper end of the bottle, so as to effectually exclude air therefrom, it is only necessary to turn or elevate the free end of the lever a limited distance, so that it is free from contact with the bottle, and the lever can then be turned in a horizontal plane, to likewise actuate the bail, the collar, and the screw connected to the lever, thereby elevating the screw while the stopper remains stationary in the mouth of the bottle, being held from movement therein by frictional contact of the elastic packing with the bottle. By thus rotating the screw in the stopper the distance of the stopper-body from the fulcrum of the lever is increased, and the pressure exerted by the lever is correspondingly increased, and when the lever is again depressed until its free end 111 bears on the bottle the stopper and packing are forced more firmly into engagement with the upper edge and sides of the open mouth of the bottle, thereby more effectually closing the latter, as will be very readily understood. 115

It will thus be seen that I provide an improved bottle-stopper which can be very readily applied to any class of beer or other bottles, and which can be quickly adjusted to fit bottles of different sizes and to take up the 125 wear on the parts. The fastener can be readily applied to new bottles and adjusted so as to tightly fit the same, and it can be readily adjusted upon old bottles, to cause it to tightly fit them when they have become loose through 130 wear, &c., on the parts.

I attach especial importance to the stopper adjustably connected to the lever, so that the distance between the fulcrum of the lever and

the stopper can be varied to adapt it to fit bottles of varying sizes and take up the wear on the parts, and to connecting the parts in such a manner that they can be turned or rotated in horizontal planes without removing the device from the bottle or displacing the stopper and its packing from their positions in the open mouth of the bottle, which latter feature is very desirable in closing beer and other bottles after they have been filled, as air is thereby effectually excluded from the bottle while the operation of adjusting the parts is being performed.

In the modified form of my invention shown in Figs. 5 and 6 of the drawings I rigidly affix the regulating screw to the center of the stopper, so that it will project upwardly therefrom, and a collar or sleeve, J, is fitted on the screw and adjustable vertically thereon. This sleeve or collar is interiorly screw-threaded, and it is provided with integral trunnions j, that are located at diametrically opposite points thereon. The lever is formed with aligned eyes l, through which are passed the trunnions of the adjustable collar, and the lever is thereby connected in a pivotal manner with the collar and stopper, and in a like manner with the bail, the free ends of the lever being bent or doubled around the bail, as heretofore described.

The operation of this form of my invention is substantially the same as the device heretofore described, with the single exception that the collar in this case is adjusted vertically, instead of the screw, to vary the distance of the stopper from the fulcrum of the lever.

It will be understood that in both forms of my invention, whether I use a bracket formed integral or held rigid with the screw, or have a collar to work on the screw, the latter being held rigid, the same general feature is observed. The bracket or collar that forms the fulcrum for the lever is vertically adjustable in both instances by the movement of the lever.

It is obvious that the improvements herein described can be applied to jars for fruit, the parts being enlarged and changed to accommodate the new application; hence I do not wish to be restricted to bottles in the use of my improved stopper.

Having thus fully described my invention, what I claim as new, and desire to secure by Letters Patent, is—

1. The combination, with a collar fitted loosely upon a bottle or the like, and capable of a free rotary motion around the same, of a bail pivoted to the collar and moving therewith in its rotary motion, a lever connected to the bail, the stopper, and an adjustable moving fulcrum for the lever, which fulcrum is connected to the stopper, and is adjustably operated solely by the movement of the lever, as set forth.

2. The combination of the bail connected to a bottle or the like, so as to be capable of a free rotary movement in a horizontal plane,

the lever, the stopper, and the movable fulcrum for the lever connected to the stopper, which fulcrum is connected to the bail, and is adjustably operated solely by the movement of the lever, so as to turn in a horizontal plane independently of the stopper, as set forth.

3. In a stopper for bottles and the like, the combination of a bail, a screw connected to the stopper, and a lever fulcrumed upon the screw and connected to the bail, whereby the distance between the stopper and the fulcrum of the lever can be varied to regulate the pressure of the lever upon the stopper, substantially as described, for the purpose set forth.

4. The combination of a collar loosely fitted upon a bottle or the like and capable of rotary motion around the same, a bail pivoted to the collar and movable therewith, a stopper, a lever pivoted to the bail, and a screw intermediate of the stopper and lever and having the latter fulcrumed upon the same, substantially as described, for the purpose set forth.

5. The combination of a collar fitted loosely upon a bottle and capable of free rotary motion around the same, a bail pivoted to the collar and moving therewith in its rotary motion, but capable of an independent swinging motion, a lever pivoted to the bail, and a screw connected to the stopper and having the lever fulcrumed upon the same, whereby the distance between the stopper and the fulcrum of the lever can be varied, and the lever, the bail, and collar are capable of a horizontal rotary motion independently of the stopper, substantially as described, for the purpose set forth.

6. The combination of a stopper having the threaded socket, the screw adjustably connected to the socket of the stopper, the bail, and a lever fulcrumed upon the screw and pivoted to the bail, substantially as described, for the purpose set forth.

7. The combination of a stopper having the threaded socket and the elastic packing connected thereto, the screw working in the socket and having the head provided with the aligned ears, the lever fulcrumed in the ears of the screw, and the bail to which the lever is connected, substantially as described, for the purpose set forth.

8. The combination of a stopper, the adjusting-screw connected therewith, a collar, a bail pivoted to the collar, and a lever connected to the bail and having the pivot-arms thereof arranged out of its longitudinal axis and fulcrumed to the adjusting-screw, substantially as described, for the purpose set forth.

In testimony that I claim the foregoing as my own I have hereto affixed my signature in presence of two witnesses.

WILLIAM WERTS.
